(57) **CLAIM**

The ornamental design for a hair clipper, as shown and described.

DESCRIPTION

FIG. 1 is a first perspective view of a hair clipper showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of a portion of the hair clipper taken from FIG. 1; and,

FIG. 10 is an enlarged view of a portion of the hair clipper taken from FIG. 2.

The evenly spaced broken lines illustrate portions of the hair clipper and form no part of the claimed design. The dash-dot-dash broken lines illustrate the boundaries for the enlarged detail views and form no part of the claimed design.
